UNITED STATES PATENT OFFICE.

HENRY C. HAZZARD, OF SAN FRANCISCO, CALIFORNIA.

DESIGN FOR A GAME-BOARD.

47,487.

Specification for Design.

Patented June 22, 1915.

Application filed May 3, 1915. Serial No. 25,617. Term of patent 14 years.

To all whom it may concern:

Be it known that I, HENRY C. HAZZARD, a citizen of the United States, residing in the city and county of San Francisco, State of California, have invented a new, original, and ornamental Design for Game-Boards, of which the following is a specification, reference being had to the accompanying drawings, forming part thereof.

The figure is a plan view of the game board, illustrating my design.

I claim:

The ornamental design for a game board, substantially as shown.

HENRY C. HAZZARD.

Witnesses:

H. JEFFREY,
LE GRAND BROWN.
